UNITED STATES PATENT OFFICE.

FRANK A. HOWARTH, OF NEW YORK, N. Y.

AIR-OPERATED SPRAYING MEANS.

Application filed February 17, 1926. Serial No. 88,821.

This invention relates to spray devices and more particularly to air operated means for spraying paint, colors, disinfectants and the like, though it is noted that the invention 5 is not limited to any of these, nor in some respects even to spray devices.

One object of the invention is to provide in an apparatus or device of this kind improved valves for controlling the liquid- 10 spraying, or cleaning with air the objects to be sprayed, and improved means for conveniently manipulating the valves while the device is held in the hand.

Another object of the invention is to provide in an apparatus or device of this kind, improved nozzle means for atomizing and spraying the liquid.

Another object of the invention is to provide improved means for preventing drip 20 from the liquid discharge nozzle.

Other objects of the invention are to improve generally the simplicity and efficiency of such devices and to provide a device or apparatus of this kind which is convenient, 25 economical, durable and reliable in operation, and economical to manufacture.

Still other objects of the invention will appear as the description proceeds; and while herein details of the invention are described 30 and claimed, the invention is not limited to these, since many and various changes may be made without departing from the scope of the invention as claimed in the broader claims.

The inventive features for the accomplishment of these and other objects are shown herein in connection with an improved spray device which, briefly stated, includes a block mounted on a container and provided with a pair of chambers each having a valve across 35 the chamber actuated by exterior manipulat- 40 ing means disposed near a handle carrying the device. Suitable means introduce air from a hose into the chambers on the inlet side of the valve; and cleaning and eduction nozzles receive air from the chambers respectively on the discharge side of the valves. A tube in the container is formed with a conical discharge head apertured through an apex, the eduction nozzle being 45 provided with a jet aperture alined with said apex, and additional perforations for cleaning said head of drip.

In the accompanying drawing, showing 50 by way of example, one of many possible embodiments of the invention,

Fig. 1 is a side elevation of the device part-

ly in longitudinal vertical section, the section being taken on the line 1—1 of Fig. 3, looking in the direction of the arrow of said line;

Fig. 2 is a fragmental elevation showing the several nozzles of the spray device;

Fig. 3 is a fragmental rear elevation showing the air control manipulating means; and

Fig. 4 is a longitudinal axial sectional view, 65 showing the eduction nozzle.

My improved spray device is shown in combination with a container 5 having an exteriorly threaded mouth on which is screwed an interiorly threaded cap 6 provided with a vent 7.

A block 9 mounted on said cap is provided with a pair of forwardly and upwardly inclined valve receiving bores or chambers 10, each tapped at both ends and having an enlarged forward portion forming an intermediate forwardly facing shoulder 11 on which rests a valve seat 12 having a central passage opening each receiving a valve ball 15 adapted to close the passage opening. A helical spring 16 is compressed between a washer 17 resting on the ball and a screw plug 18 in the upper end of each chamber, whereby the ball is yieldably closed on the seat.

A transverse bore 20 (Fig. 3) passes 85 through the upper portion of the chambers 10 and a boss 21 on one side face of the block. A coupling ferrule 22 received on said boss is provided with bayonet slots 23 receiving the ends of a transverse pin 24 passing through 90 said boss and is provided with a hose receiving nipple 25 whereby air under pressure may be communicated to the upper part of the chambers to press the balls upon the seats.

Threaded bushings 30 (Fig. 1) in the lower 95 ends of said chambers, each slidably receives a push rod 31 provided with a milled outer manipulating button 32, an intermediate retaining shoulder 33 engageable with the inner face of the bushing, and a pointed inner 100 end 34 engageable with the ball to push it off its seat, to open the valve when the button is pressed, thereby to communicate the air pressure to the lower part of the chamber and forward air passages 35 extending from the lower part of the chambers respectively.

An upwardly and then forwardly directed pipe 37 screwed in the tapped end of one of 105 said forward passages is formed with a forwardly directed cleaning blast nozzle 39 for pre-cleaning the work that is to be sprayed.

A hollow inwardly open eduction-nozzle

plug 40 in the tapped end 41 of the other forward passage 35 has a thick outer end wall 42 (Fig. 4) provided with a small axial education or jet aperture 43 (Fig. 2) and a pair 5 of axially parallel lateral perforations 44 at each side of said aperture below the level thereof.

A threaded opening in said cap just forward of said nozzle plug receives a tube 47 10 (Fig. 1) extending to near the bottom of said container and provided with a threaded enlarged upper end 48 screwed in said opening and formed with an upwardly pointing conical discharge head 49 having a knurled adjusting rim 50 and a vertical discharge aperture 51 communicating with the tube and passing out through the apex 52 of the head. A knurled jam nut 53 on said enlarged end is engageable with said cap to adjustably 20 position said apex to be in line with said axial aperture 43, whereby air from the axial aperture, blowing across said apex, draws the liquid up the tube and discharge aperture and atomizes and sprays the liquid in a 25 direction generally forward of the education nozzle 40, air from said lateral perforations 44 serving to clean the discharge head of any drip of liquid from its apex.

The block 9 is provided with a middle 30 tapped bore 55 (Fig. 3) receiving the stem 56 of a handle 57. Said stem is disposed between said buttons 32 and carries a downwardly and rearwardly disposed grip 58 terminating at its upper end near said buttons in convenient position for the thumb of the hand holding the grip to manipulate either button without removing the thumb from the other button, to apply cleaning air or paint or other liquid to the material or 40 object to be sprayed. It will thus be seen that I have provided means adapted to actuate the air blast means to clean the material or object to be sprayed by merely having pressure applied on it by the operating finger that is resting partly on the spray nozzle button—without removing the finger from the spray nozzle button.

The operation of the device is very simple and convenient. After a suitable paint or 50 coloring matter or other liquid to be sprayed has been placed in the container, and air or other gaseous pressure has been introduced through a suitable hose on the nipple 25 into the upper part of the chambers 10, the device is ready to operate, and is held in the hand by the grip 58 with the thumb resting on both buttons ready to apply pressure to either button 32.

If it is desired to dust off or dry or otherwise clean the article to be sprayed, one button 32 is pressed to liberate a blast of air to the nozzle 39; and after the article has been cleaned the other button is pressed to 65 emit air from the jet aperture 43 thereby to

draw the liquid up the aperture 51 and atomize and spray it forward of the device. The spraying continues only so long as the proper button is pressed.

I claim as my invention:

1. In a device of the character described the combination with a container having a pipe therein for passage therethrough of the contents of the container, of a member having a chamber therein for compressed air and an outlet for the compressed air from the chamber, and a discharge nozzle cooperating with said outlet, said nozzle being adapted and disposed for cooperating with the discharge end of said pipe for drawing the contents of the container out through said pipe by induction of the compressed air discharged by said nozzle and atomizing and spraying said drawn-out contents and being provided with means for clearing from the exterior surface of the discharge end of said pipe the drip of said drawn-out contents.

2. In combination, a block provided with a forwardly and upwardly inclined valve receiving chamber, tapped at both ends and having an enlarged forward portion forming an intermediate forwardly facing shoulder, and a forward air passage from the lower part of the chamber; a valve seat resting on said shoulder having a central passage opening; a ball adapted to rest on said seat to close the passage opening; a washer resting on said ball; a screw plug in the upper end of the chamber; a helical spring in each chamber compressed between the plug and washer, 95 whereby the ball is yieldably closed on the seat; means for introducing compressed air to the upper portion of the chamber; a threaded bushing in the lower end of said chamber; a push rod slidably in said bushing 100 and provided with an outer manipulating button, an intermediate retaining shoulder engageable with the inner face of the bushing, and a pointed inner end engageable with the ball to push it off its seat; and a nozzle terminating said forward passage.

3. In combination, a block provided with a pair of forwardly and upwardly inclined valve receiving chambers, each having an enlarged forward portion forming an intermediate forwardly facing shoulder; a transverse bore traversing the upper portion of the chambers and one side face of the block, forward air passages from the lower part of the chambers respectively and having tapped forward ends; valves across each chamber on said shoulder; means for introducing fluid under pressure into the transverse bore; and fluid directing means receiving air from the forward passage.

4. In a device of the character described, the combination with a pipe for passage of liquid therethrough having on its discharge end a conical nozzle provided with an aperture at its apex, of a second nozzle 130

- provided with an aperture for discharging at a right angle to the aperture of the first nozzle fluid under compression for drawing the liquid out through the first nozzle by induction of the discharged fluid and provided with apertures arranged in the same plane in the second nozzle and below the plane of the first mentioned aperture of the second nozzle for discharging the fluid under compression along the conical sides of the first nozzle and substantially parallel to the plane of discharge of the induction fluid from the second nozzle for clearing the exterior sides of the apex of the first nozzle of the drip of the drawn-out liquid.
5. In a device of the character described, in combination, a paint container, a cap on said container, a housing associated with said cap, a chamber in said housing having means for 10 inlet of air under pressure into one end of the chamber, air blast nozzle means associated with said chamber adapted to clean a surface prior to coating with paint, a valve seat member arranged intermediately of the 15 ends of said chamber transversely of the chamber and having a valve opening therethrough, a ball valve disposed in said chamber at the air inlet end thereof for cooperat-

ing with said valve seat, and a push member located in said chamber at the end thereof opposite the air inlet end and having a slimly pointed end portion passing through said valve opening and engaging said ball valve for moving the valve from closing position to open position whereby air passes through said valve opening from the air inlet end of said chamber to the nozzle means.

6. In combination, a container, a cap thereon, a block mounted on said cap provided with an elongated chamber, a boss on one side face, and a transverse bore across the upper portion of said chamber and surrounded by said boss, a transverse pin passing through said boss, and a coupling ferrule received on said boss and provided with bayonet slots receiving the ends of the pin, and provided with a hose receiving nipple, whereby air under pressure is communicated to the upper part of the chamber, a nozzle receiving air from the chamber, and liquid supply means cooperating with the nozzle to produce a paint spray.

Signed at New York, in the county of New York, and State of New York, this 16th day of February, A. D. 1926.

FRANK A. HOWARTH.
